UNITED STATES PATENT OFFICE.

JASPER LOCKWOOD, OF LAUREL, INDIANA.

TUG-FASTENER.

SPECIFICATION forming part of Letters Patent No. 700,345, dated May 20, 1902.

Application filed October 5, 1901. Serial No. 77,735. (No model.)

To all whom it may concern:

Be it known that I, JASPER LOCKWOOD, a citizen of the United States, residing at Laurel, in the county of Franklin and State of Indiana, have invented a new and useful Improvement in Tug-Fasteners, of which the following is a specification.

This invention is an improved construction of tug-fastener, the object being to provide a cheap, simple, and efficient appliance capable of attachment to any and all whiffletrees now in use and by means of which the tug can be securely and automatically fastened upon the end of the said whiffletree.

With this object in view the invention consists, essentially, of a metallic ferrule adapted to be fitted upon the end of the whiffletree, said ferrule having an opening in which is pivoted a lug, said lug having a leaf-spring bearing against the end, said spring being connected to the ferrule or thimble upon the inner side and resting within a groove produced in the end of the whiffletree.

The invention consists also in certain details of construction and novelties of combination, all of which will be fully described hereinafter and pointed out in the claim.

In the drawings forming part of this specification, Figure 1 is a perspective view showing the practical application of my invention. Fig. 2 is a longitudinal sectional view of the same. Fig. 3 is a section on the line 3 3 of Fig. 2. Fig. 4 is a top plan view.

Referring to the drawings, A indicates the end of the whiffletree, having a longitudinal groove A' produced in the upper face of the same. The metallic ferrule or thimble B is fitted over the end of the whiffletree and secured in any suitable manner. This ferrule or thimble has a longitudinal opening B' arranged directly above the groove A'. At the end of said opening the side edges are pressed upwardly, as shown at B², in order to form bearings for the pivot C, carrying the fastening-lug D, the inner end of said lug being flattened, as shown at D', and bearing against a leaf-spring E, which rests within the groove

and is securely fastened at E' upon the inner side of the ferrule or thimble. The ferrule or thimble is forced outwardly, as shown at 50 F, to receive the said spring, and beyond the opening the upper face of the ferrule or thimble is forced outwardly, as shown at G, to receive the free end of the spring and also serve as a stop to limit the outward movement of 55 the fastening-lug.

In operation the tug is forced over the end of the ferrule or thimble and the lug is pressed downwardly and inwardly, the groove in the whiffletree permitting such movement of the 60 spring, and the tug can be quickly and easily forced over the lug in its folded position. The moment, however, the tug has passed the fastening-lug the spring will force it back to its normal or upright position, and thereby prevent the tug working off the end of the whiffletree, and the portion G will act as a shoulder to limit the outward movement of the lug D, and thereby prevent the tug forcing the same outwardly. 70

Having thus fully described my invention, what I claim as new, and desire to secure by Letters Patent, is—

The combination with a whiffletree, the end of which is grooved longitudinally, of a ferrule or thimble arranged thereon, said ferrule or thimble having an opening adapted to align with the groove in the whiffletree, bearing-recesses produced adjacent to the end of the said opening, a lug arranged at the end 75 of the opening; the pivot passing through the lug and resting in the bearing-recesses, a spring secured within the ferrule, the free end bearing against the flattened end of the lug, the upper face of the ferrule or thimble 80 being forced upwardly to accommodate the free end of the spring and serve as a stop-shoulder for the lug, substantially as shown and described. 85

JASPER LOCKWOOD.
